United States Patent Office

Des. 204,639
Patented May 3, 1966

204,639

PAIR OF SUNGLASSES

George R. Hoffmaster, Esterly, and Palmer E. Brace,
Mohnton, Pa., assignors to The Electric Storage Battery
Company, Philadelphia, Pa.

Filed Oct. 23, 1965, Ser. No. 87,876

Term of patent 14 years

(Cl. D57—1)

Fig. 1.

Fig. 2.

Fig. 3.

FIG. 1 is a front elevational view of a pair sunglasses, showing our new design;

FIG. 2 is a bottom view thereof; and

FIG. 3 is a top view thereof, with portions of the temple shown broken away for convenience of illustration.

The dominant features of my design reside in the portions shown in full lines.

We claim:

The ornamental design for a pair of sunglasses, substantially as shown and described.
